UNITED STATES PATENT OFFICE.

AUGUST SCHMIDT, OF CINCINNATI, OHIO, ASSIGNOR OF ONE-HALF TO
JOHN SCHMED, OF SAME PLACE.

MACHINE FOR PRODUCING ORNAMENTAL SURFACES ON TEXTILE FABRICS.

SPECIFICATION forming part of Letters Patent No. 334,477, dated January 19, 1886.

Application filed February 9, 1885. Serial No. 155,412. (No model.)

To all whom it may concern:

Be it known that I, AUGUST SCHMIDT, a citizen of the United States, residing at Cincinnati, Ohio, have invented new and useful 5 Improvements in Machines for Producing Ornamental Surfaces on Textile Fabrics, of which the following is a specification.

My invention relates to that class of machines heretofore used for producing "flutes" or "crimps" in textile fabrics for temporary ornament, and commonly called "fluting-machines;" and it consists in the machine hereinafter described, for producing a different style of ornamental surfacing in such fabrics—15 to wit, protuberances, in any systematic arrangement adapted to the operation of the machine, as hereinafter more fully described.

Mechanism embodying my invention is illustrated in the accompanying drawings, in 20 which—

Figure 1 is a perspective view of my apparatus complete; Fig. 2, a side elevation of the same; Fig. 3, a vertical cross-section taken axially through the pressing-roller centrally through its manipulating-handle, and 25 Fig. 4 a vertical cross section of the roller and part of the base-plate at an intermediate point between the ends of the roller.

As indicated in the drawings, my improved 30 apparatus consists of a flat base-plate, A, on the upper surface of which are protuberances a, arranged in definite series, according to the pattern to be produced in the fabric, and a roller, B, pivotally mounted in side lugs, c, 35 securing it to a handle, H. The base-plate A is preferably cast of metal—such as brass, or zinc, or block-tin—in an encircling iron frame, a'; and the roller is cast hollow, for the insertion of a heating-iron, b', but with a smooth 40 exterior peripheral surface, in which I drill openings or cavities b, corresponding with the protuberances a of the base-plate.

To accommodate the insertion of the heating-iron b', one end of the hollow roller B is 45 left open, the pivotal connection being by

means of an annular flange surrounding this opening, which opening is exteriorly closed by a pivoted gate, c', upon one of the lugs c. The lugs c are fastened at their upper ends to a cross-bar, e, to which is attached a manipulating-handle, H, as shown.

The fabric to be operated upon, properly starched and dampened, is placed upon the base-plate across the protuberances a, and the roller, suitably heated, is then pressed down 50 and rolled over the fabric in such manner that the cavities of the roller fit over upon the protuberances of the base-plate, pressing the fabric between, forming the surface of the fabric into protuberances corresponding with those 55 of the base-plate, which are "set" by the starch of the material under the heat of the roller, producing a very attractive ornamental surfacing of the goods.

It will readily be perceived that the general 60 features of the design may be altered by changing the arrangement of the protuberances and cavities correspondingly.

I claim as my invention and desire to secure by Letters Patent of the United States—

The improved machine for ornamenting textile fabrics, consisting, substantially, of a base-plate having protuberances upon its surface, arranged in separate series both longitudinally and transversely of the plate, and a hollow roller provided with a manipulating-handle and having in its peripheral surface pits or cavities corresponding with the protuberances of the base-plate, said roller having one end open for the insertion of a heating-iron 75 and provided with a closing gate, as and for the purpose set forth.

In testimony whereof I have hereunto set my hand in the presence of two subscribing witnesses.

AUGUST SCHMIDT.

Witnesses:

JOHN SCHMID,
L. M. HOSEA.
